[57] CLAIM

The ornamental design for a table leg or similar article,
as shown and described.

DESCRIPTION

FIG. 1 is a perspective view of a table leg or similar
article, showing my design;

FIG. 2 is a front elevational view;

FIG. 3 is a rear elevational view;

FIG. 4 is a side elevational view; the opposite side being
a mirror image thereof;

FIG. 5 is a top plan view; and,

FIG. 6 is a bottom plan view thereof.

*Fig. 1**Fig. 2**Fig. 4*

*Fig. 3**Fig. 5**Fig. 6*
